DRUM LOCK

Frank W. Meyer, East St. Louis, Ill.

Application June 5, 1935, Serial No. 25,077

5 Claims. (Cl. 70—125)

The object of this invention is to provide a lock for drums or containers of liquids that are exposed to tampering with by unauthorized persons or theft of their contents.

5 Local laws in many places forbid keeping drums for alcohol inside of buildings. When stored outside, mischievous persons often turn the faucets and allow the contents to waste. Still more frequently, thieves open the faucets 10 and steal the contents.

This invention consists of a strong, simple, compact, effective, and cheap lock to overcome such conditions and, also, a device for that purpose that is easy to understand and operate and 15 one which can be quickly applied and removed.

Its use is not limited to containers of liquids, if the construction of the container bears a projection for its attachment like the faucet herein shown.

20 In the accompanying drawings, in which like numbers of reference denote like parts wherever they occur,

Fig. 1 is a side elevation of a drum, with the lock in position thereon.

25 Fig. 2 is an end elevation of a modified form of drum, with the lock in place.

Fig. 3 is a side elevation of the main locking device.

30 Fig. 4 is an elevation thereof, showing the part that faces the end of the drum.

Fig. 5 is a plan view of the subject-matter of 35 Figs. 3 and 4, looking downward in the said views of the drawings.

Fig. 6 is a fragmentary view of the subject-matter of Fig. 4, showing the cap of the drum with the top part of the locking device and 40 padlock in place.

Fig. 7 shows a modification of the hood of the lock in position, covering the faucet, and a fragmentary view of the drum.

45 Fig. 8 is a side elevation of one part of the lock when the drum is provided with a bunghole in the side of the drum in addition to one in the end.

Fig. 9 is a plan view of the same. Fig. 10 shows a modification of the locking device, to be used on drums where the faucet is in the end of the drum and there is only one bunghole, located in the side of the drum.

50 Fig. 11 is a plan view of the same. Fig. 12 is a fragmentary view of part of the device of Fig. 11, showing how the bars may be adjusted for variation in the position of the bunghole.

55 Fig. 13 is a plan view of the bunghole cap.

Fig. 14 is an enlarged side elevation of the same.

Fig. 15 is a side elevation of another form of cap.

In Fig. 1, the drum 1 is provided with an opening or bunghole 2 in its end and another opening or bunghole 3 in its side. A cap 4 closes opening 2, and cap 5 plugs opening 3. Each of the said caps and holes is threaded.

Faucet 6 is threaded at 7 and screwed into opening 8 in the end of drum 1. Hood 9 is adapted to inclose faucet 6 and is made of metal to protect faucet 6 from being opened. Hood 9 is borne by bar 10, which is securely fastened to its side or bottom that faces the end of drum 1. Brace 11 additionally secures hood or housing 9 to bar 10. Bar 10 is notched at 12, so as to provide a fork that fits around faucet 6. The other end of bar 10 bears projection 13, preferably made integral therewith, containing a notch 14, adapted to receive an angle of the polygonal cap or nut 4, from which projects a lug 15, containing an eye 16, through which may be passed the hasp 17 of a padlock 18, to lock the hood 9 over faucet 6 when the parts are in the positions shown in Figs. 6 and 7. Notch 14 prevents the rotation of cap 4. Likewise, if, on account of expansion or contraction, due to heat or cold, the fit of an angle of cap 4 into notch 14 is not tight, the flat side edge 19 may fit tightly against the straight front edge 20 of projection 13, equally preventing rotation of cap 4. The drawings show cap 4 as a hexagonal nut, but it may be quadrilateral or otherwise polygonal. The flat sides or corners of these other shapes of nuts will hold the same from rotation in the same way as above explained with regard to the hexagonal form.

The notched corner 21 in the hood 9 and the flange or projection 22 on drum 1 in Fig. 7 illustrate a modification of construction from that illustrated in Fig. 3. The countersink 23 in Fig. 2 shows a difference in construction of drum 1 from that shown in Fig. 7.

The lock for opening 3 (when there is such an opening in the side of the drum 1, as shown in Fig. 1) may be combined with the lock for faucet 6 and opening 2, as hereinbefore described, as illustrated in Fig. 1, in which the bar 24 is provided with an arm 25 at substantially a right-angle thereto, containing an eye 26, adapted to fit over lug 15 and to be locked thereon by the padlock 18 in the same manner and at the same time as bar 10.

The other end of bar 24 is preferably pro-

vided with a pair of ears 27, depending from the branches 23 of a fork. The said fork fits around shank 29 of the form of cap shown in Figure 15 and is held in place thereon by head 30, while the ears 27 fit alongside two opposite flat sides 31 of the polygonal nut or cap 5.

One difference between the bar 24 shown in Figs. 1, 8, and 9 and the construction appearing in Figs. 10 and 11 is the provision of the hinge 33 between the analog of the bar 24 and the bar 10'. This unites in one device the locking members for both the faucet 6 and the opening 3 in the side of the drum.

The location of the opening 3 is not uniform in all drums containing an opening in the side, some being nearer and others farther from the end where the faucet 6 is located. This difference in construction can be accommodated by adjusting the straps 34 and 35 by sliding the same relative to each other, the rivets 37 being inserted in the holes 38 that will make the most accurate adjustment and hold it. The straps 34 and 35 take the place of the bar 24.

The lug 15 on cap 4 passes through an eye 32 in bar 10, as shown in Figs. 1, 2, and 6.

The eye 46 in strap 35 as shown in Fig. 11 serves the same purpose in this modification as eye 32 shown in Figs. 3 and 4.

The bar 39 shown in Figs. 10 and 11 is securely fastened to bar 10' and, by contacting the projection 22 of drum 4, prevents bar 10 and strap 34 from being moved from side to side.

When the lock is to be applied, the hood or housing 9 is fitted over faucet 6, and the fork formed by notch 12 slipped around faucet 6, and the bar 10 moved as far toward the faucet 6 as possible, making it possible for lug 15 to pass through the eye 32 in bar 10. The hasp 11 of the padlock 18 can then be inserted through the eye 16 in lug 15. If an opening 3 in the side of the drum 4 is also to be locked, the bar 24 and the arm 25 will have been put in position for that purpose, with lug 15 passing through eye 26 before the padlock is slipped through eye 16. When the device of Figs. 9 and 10 is used, the mode of attachment will be similar, that is to say, the fork formed by notch 12 will be pressed closely against the faucet 6 before the bar 24 of that device is fitted to lock the hole 3 in the side of the drum.

It will be obvious that many minor changes may be made in the form and arrangement of the several parts of this device without departing from the spirit of this invention or the scope of the following claims.

Having thus described this invention, what is claimed and desired to be secured by Letters-Patent is:

60 1. In a locking device for a container having a discharge port with a valved closure and a filling port with a threaded closure, a bar for extension between and beyond said closures, said bar having a notch in one end for receiving the discharge port closure, means adjacent said notch for preventing access to the discharge port closure, said bar further having an opening adjacent the filling port closure for receiv-

ing a portion of the latter therethrough, lock means for preventing withdrawal of the bar from the filling port closure, and means adjacent said opening for engagement with the filling port closure for preventing rotation of 5 the latter.

2. In a locking device for a container having a discharge port with a valved closure and a filling port with a threaded closure provided with a polygonal peripheral face, a bar for extension between and beyond said closures, said bar having a notch in one end for receiving the discharge port closure, means adjacent said notch for preventing access to the discharge port closure, said bar further having an opening adjacent the filling port closure for receiving a portion of the latter therethrough, lock means for preventing withdrawal of the bar from the filling port closure, and a projection on the bar and having a flat face for engagement with the peripheral face of the filling port closure to prevent rotation of the latter.

3. In a locking device for a container having a discharge port with a valved closure and a filling port with a threaded closure provided with a polygonal peripheral face, a bar for extension between and beyond said closures, said bar having a notch in one end for receiving the discharge port closure, means adjacent said notch for preventing access to the discharge port closure, said bar further having an opening adjacent the filling port closure for receiving a portion of the latter therethrough, lock means for preventing withdrawal of the bar from the filling port closure, and a projection on the bar and having a notch for engagement with the peripheral face of the filling port closure to prevent rotation of the latter.

4. In a locking device for a flanged container having a discharge port with a valved closure 40 and a filling port with a threaded closure, a bar for extension between and beyond said closures, said bar having a notch in one end for receiving the discharge port closure, means adjacent said notch for preventing access to the discharge port closure, said bar further having an opening adjacent the filling port closure for receiving a portion of the latter therethrough, lock means for preventing withdrawal of the bar from the filling port closure, means adjacent 45 said opening for engagement with the filling port closure for preventing rotation of the latter, and a cross-bar secured to said bar for engagement with the flange of the container on opposite sides of said bar.

5. In a locking device for a container having a multiplicity of ports and closures one of which is a discharge port having a valved closure, a bar for extension between and beyond said closures, said bar having flanges and openings to 60 receive parts of the said closures and prevent rotation thereof, a notch in one end for receiving the said discharge port, means adjacent said notch for preventing access to the valved closure, and locking means extending through one 65 of the said closures for preventing removal of this device.

FRANK W. MEYER.
